No. 739,327.

PATENTED SEPT. 22, 1903.

W. D. LINK.

FIRE EXTINGUISHING APPARATUS.

APPLICATION FILED SEPT. 13, 1902.

NO MODEL.

UNITED STATES PATENT OFFICE.

WILLIAM D. LINK, OF TALLADEGA, ALABAMA.

FIRE-EXTINGUISHING APPARATUS.

SPECIFICATION forming part of Letters Patent No. 739,327, dated September 22, 1903.

Application filed September 13, 1902. Serial No. 123,242. (No model.)

To all whom it may concern:

Be it known that I, WILLIAM D. LINK, a citizen of the United States, residing at Talladega, in the county of Talladega and State 5 of Alabama, have invented new and useful Improvements in Fire-Extinguishing Apparatuses, of which the following is a specification.

This invention relates to fire-extinguishing 10 apparatuses; and it consists in certain improvements in the construction thereof, as will be hereinafter fully described, and pointed out in the claims.

The invention is illustrated in the accompanying drawings, as follows:

Figure 1 shows a section on the line 1 1 in Fig. 2. Fig. 2 shows a front elevation of the apparatus. Fig. 3 shows a section on the line 3 3 of the fragile cap and mechanism incident 20 thereto.

A marks the inlet-passage. This is connected with the fire-extinguishing-fluid supply, preferably steam.

Extending from the passage A is a flange 25 a, and secured to this flange is the flange b² of the fragile cap B. The fragile cap forms a closure for the passage A. It has the annular groove b, which decreases the thickness of the cap to such an extent that it may be 30 readily broken by transverse pressure exerted at the outer end of the cap. An inclosing means C is also secured to the flanges a and b² and forms a housing for the cap B. This inclosing cap or means has the opening c. A 35 small piece of pipe E rests on the end of the cap B and extends up through this opening. The outer end of the cap B is provided with a slot b'. A rod D extends through the pipe E and slot b' and rests in the socket C' at the 40 bottom of the inclosing cap C. The rod D forms a guide for a weight F. The weight F is normally held in its upper position by means of the chain G. A trip-lever I is arranged to hold the lever H normally in a horizontal 45 position. The link J is arranged to hold the trip-lever in position to accomplish this result. A portion K of the link J is of material very sensitive to heat and forms a fuse-link. Upon the breaking of the fuse-link K incident to abnormal heat the trip-lever I releases the lever H, and this in turn releases the weight F. The weight F, falling

on the pipe E, exerts sufficient strain on the end of the cap B to break it along the annular groove b. The action of steam upon the cap 55 B forces it into the upper part of the cap C and out of the main passage of steam. The moving steam holds the cap B in this upward position. The slot b', engaging the rod D, prevents a forward movement of the cap B, and 60 thus avoids the clogging of the passage by such action.

Secured to the inclosing cap C is a distributing system consisting of the pipe L and the nozzles l. This distributing system may be 65 as extensive as desired. Immediately adjacent to the cap C is a whistle-pipe M, on which is attached a whistle N, the extended pipe on the system L exerting sufficient back pressure to sound the alarm through the whistle N. In case of fire, the weight being released, as above stated, the cap B is broken and forced out of the way of the moving steam, steam passes into the pipe L, blows the whistle, and is distributed by means of the nozzles l. 70

What I claim as new is—

1. In a fire-extinguishing apparatus the combination of the passage for conveying fire-extinguishing material; a fragile cap for said passage; and inclosing means for said fragile cap; distributing means leading from said inclosing means; devices for breaking said fragile cap; and means acting with a predetermined temperature for setting said devices 85 in motion.

2. In a fire-extinguishing apparatus the combination of the passage for conveying fire-extinguishing material; a fragile cap for said passage, said cap having a line or part of sufficient weakness to determine the line of fracture; devices for breaking said fragile cap; and means acting with a predetermined temperature for setting said devices in motion. 90

3. In a fire-extinguishing apparatus the combination with a passage for conveying fire-extinguishing material; a fragile cap for said passage said cap having a part of sufficient weakness to determine the line of fracture when subjected to transverse strain; an inclosing means for said fragile cap; distributing means leading from said inclosing means; devices for exerting transverse strain on said fragile cap; and means acting with a 100

predetermined temperature for setting said devices in motion.

4. In a fire-extinguishing apparatus the combination of a passage for conveying fire-extinguishing material; a fragile cap for said passage; an inclosing means for said fragile cap, said inclosing means and fragile cap being arranged to effect a movement of the fragile cap incident to the flow of steam out of the line of passage; devices for breaking said cap; and means acting with a predetermined temperature for setting said devices in motion.

5. In a fire-extinguishing apparatus the combination of a passage for delivering fire-extinguishing material; a fragile cap for closing said passage; and an inclosing means for said cap, said means being arranged to retain the fragments of said fragile cap when broken; and means for acting with said inclosing means, and the cap for preventing the fragments of the cap from clogging the passage.

6. In a fire-extinguishing apparatus the combination of the passage A; of the cap B having the annular groove b and slot d'; the inclosing means C having the opening c; the pipe E arranged in the opening c and resting upon the cap B; the rod D extending through

the pipe E and slot b'; the weight F arranged on the rod D; and means for releasing the weight F with a predetermined temperature.

7. In a fire-extinguishing apparatus the combination of the passage A; of the cap B having the annular groove b and slot d'; the inclosing means C having the opening c; the pipe E arranged in the opening c and resting upon the cap B; the rod D extending through the pipe E; a connection on the inclosing means C leading to the whistle-pipe M; and said whistle N.

8. In a fire-extinguishing apparatus the combination of the passage A; of the cap B having the annular groove b and slot d'; the inclosing means C having the opening c; the pipe E arranged in the opening c and resting upon the cap B; the rod D extending through the pipe E and slot b'; the weight F from the predetermined pressure; the pipe L secured in the inclosing means C; and the nozzles l on the pipe L.

In testimony whereof I have hereunto set my hand in the presence of two subscribing witnesses.

WILLIAM D. LINK.
